UNITED STATES PATENT OFFICE

2,489,673

FUR FINISHING IRON

Frank H. Richterkessing, Louisville, Ky.

Application March 13, 1948, Serial No. 14,790

7 Claims. (Cl. 69—20)

1

This invention relates to an improved iron for steaming, glazing, ironing or finishing furs.

The primary object of my invention is to provide a steam-iron having a resilient pad of heat conducting material secured to a sole plate thereof, in which the surface of the pad that contacts the fur and/or guard hairs consists of a metallic wire or grid-screen of such fine mesh as to provide a gentle combing action of the fur and/or guard hairs during the steaming, glazing, ironing or finishing operation.

Another object of my invention is to provide an easily detachable flanged perimetrical frame for retaining the resilient pad of woven metallic mesh in contact engagement with the heated sole plate of the iron.

A further object of my invention is to provide a detachable resilient pad of woven metallic mesh having a pressing surface covered with a metallic wire or grid-screen, wherein the mesh serves to conduct heat from the sole plate of an iron to the wire screen, and wherein the wire screen serves to provide a combing action as it engages the fur and/or guard hairs under treatment.

Another object of my invention is to provide an iron having an electrically heated sole plate covered with a detachable pad of resilient woven metallic mesh of such density as to provide a relatively low conductivity of heat to its pressing surface, so that the pressing surface of the pad has a temperature appreciably less than that of the sole plate of the iron.

Another object of my invention is to provide an iron having a heated sole plate with channelled passageways therein through which steam is circulated, conditioned and discharged through the lower horizontal surface thereof, and wherein the said lower surface has a pad of heating-conducting resilient-material secured in contact relation therewith for receiving and distributing the steam discharged from the sole plate, and which pad is heated by the sole plate so as to maintain the steam in its conditioned state.

With reference to the accompanying drawings which are a preferred embodiment of this invention:

Figure 1 is a perspective view of the fur-finishing iron posed to show clearly a detachable resilient pad within a frame and its relation to the sole plate of the iron.

Figure 2 is a front end elevation of the iron.

Figure 3 is a rear end elevation of the iron partially in section to show a portion of the detachable pad, the base and heating element, each in section.

2

Figure 4 is an elevation of the rear end of the base member of Fig. 3 without the shoe and on a reduced scale.

Figure 5 is a section in plan of Fig. 4 along line 5—5 of Fig. 4.

Figure 6 is a sectional elevation of the base member at line 6—6 of Fig. 5.

Figure 7 is a sectional elevation of the base at line 7—7 of Fig. 5.

Figure 8 is a sectional elevation of the base member at line 8—8 of Fig. 5.

Figure 9 is a sectional elevation of the pad adjacent the rear end.

Figure 10 is an elevation of the front end of the shoe.

In the present embodiment of this invention a well known commercial steam electric-iron has been utilized wherein the base-sole plate member 11 has been provided with a plurality of interconnected passageways 12, 13, 14 in which steam entering at 15 circulates and is conditioned for use through the media of, heat radiated by resistor-element 16, asbestos-wicks 17—17 and delivered into chamber 18 that is provided with ports 19—19 for discharge on to the object under conditioning treatment.

The cut away portion of Fig. 3 reveals, in sectional elevation, a resilient pad 21 of woven metal-wires and formed to cover the sole plate 20 face 20 of base 11, including ports 19—19. It should be noted that "woven metal-wire" has been specified for the material from which this pad is composed. While other substances can be substituted, the overall results are not satisfactory for regular commercial service.

The lower or "work" face 22 of the pad is of a finely woven metal grid-screen and extends, preferably, around the edge-corner 23 of the base in order to hold pad screen-frame or bezel 24 out of direct or face-to-face contact with the sole plate that is maintained at a too high temperature for application to fur. This spacing of the frame and work face 21 that, at times, contact the fur is maintained at a safe degree of heat for such use, that is, substantially lower than the sole plate, however, sufficiently high to avoid condensing the conditioned steam that is discharged from the ports to the fur through this pad and its grid-screen face.

At this point it should be noted that when the faces of the grid-screen and bottom surface of bezel 24, are used for pressing the fur, a combined combing and ironing effect is produced and that when this iron is angularly applied to the fur, with the grid screen out of contact there-

with, an ironing effect results from the smooth bottom and flange face surfaces contacting the fur.

Electric current is supplied to the resistor 16 through wire 26 through conventional apparatus. Bezel 24 together with pad 21 which assembly may be referred to as a shoe are removably attached to the iron by bolts 27-28 as shown in Figs. 1 and 3.

While it will be apparent that the illustrated embodiments of my invention herein disclosed are well calculated to adequately fulfill the objects and advantages primarily stated, it is to be understood that the invention is susceptible to variation, modification and change within the spirit and scope of the subjoined claims.

What I claim is:

1. An iron adapted for steaming and finishing fur comprising, a base member containing channeled passageways through which steam is circulated and having a plurality of discharge ports in the lower face surface thereof in communication with said passageways, means other than said steam for heating said base, a shoe for and attached to said base; said shoe having a wire mesh face overlying said ports and mounted on and within a smooth bezel having a flange surrounding said base and formed with a marginal face juxtaposed substantially parallel to and spaced from said surface.

2. A fur finishing iron comprising, a base member containing a plurality of channeled passageways through which steam is circulated and having a plurality of discharge ports in the lower face surface thereof in communication with said passageways, means other than said steam for heating the base, a resilient pad of woven metal wire attached to said base and disposed for receiving steam from the interior of the iron; said pad having a grid-screen outer face overlying the marginal edges of said lower face and mounted on and within a smooth frame having an upstanding flange surrounding and attached to said base and formed with a marginal flat face juxtaposed and substantially parallel to said surface.

3. An iron adapted for steaming or finishing fur comprising, a base member containing a channeled passageway through which steam is circulated and having a plurality of discharge ports in the lower face surface thereof in communication with said passage, a resilient pad of woven metal wire attached to said base; said pad having a grid wire face overlying the outer surface thereof and mounted on and within a smooth frame attached to said base and formed with a marginal face juxtaposed and substantially parallel to said surface.

4. An iron adapted for steaming and glazing fur comprising, a base member containing channeled passageways through which steam is circulated and having a plurality of discharge ports in the lower face surface thereof in communication with said passage, means other than said

steam for heating said base, a shoe for and attached to said base; said shoe comprising a metallic frame of angular cross section overlying and spaced from the margin of said base and edge of said face surface, a face of wire mesh disposed over said ports within said frame and a pad of resilient metallic material disposed between the lower face surface of the base and within the inside face of the wire mesh.

5. An iron adapted for steaming and glazing fur comprising, a base member containing channeled passageways through which steam is circulated and having a plurality of discharge ports in the lower face surface thereof in communication with said passage, means other than said steam for heating said base, a shoe for and attached to said base; said shoe comprising a metallic frame of angular cross section overlying and spaced from the margin of said base and edge of said face surface, a face of wire mesh disposed over the face and around the margin of the base of said iron and within said frame and a pad of resilient material disposed between the lower face surface of the base and within the inside face of the wire mesh.

6. A removable shoe for attachment to the base of a finishing iron equipped to supply radiant heat to fur comprising a frame having a flange corresponding to the contour of the edge of said base and an opening within a second flange of said frame angularly disposed to said first flange juxtaposed to and spaced from the face of said base, a metallic mesh screen within and lodged against said frame, and a metallic pad on the face of said base for resiliently retaining the margin of the screen against the inner face of said frame and the central face portion of the screen in convex relation to the plane of the face of the base of said frame.

7. A fur finishing iron comprising, a base member containing a plurality of channeled passageways through which steam is circulated and having a plurality of discharge ports in the lower face surface thereof in communication with said passageways, means other than said steam for heating the base, a resilient pad of woven metal wire attached to said base and disposed for receiving steam through said ports from the passageways; a smooth metallic frame embracing said pad and having a lower marginal face substantially parallel to the bottom of the base and an upstanding flange surrounding said base.
